CAP ADAPTABLE FOR SEALING
CONTAINERS

Allan F. Shaw, Essex, Mass.

Application August 19, 1932, Serial No. 629,447

8 Claims. (Cl. 215—38)

This invention relates to caps adaptable for sealing containers such as milk bottles, jars, and other types ordinarily used in packing and vending jams, peanut butter, or other commodities.

5 It has for its objects to provide sealing means, inexpensive to manufacture and efficient in use; to provide a sealing means which will, in addition to effecting a perfect sealing, at the same time provide protection for the exterior of the
10 container at and near the point of sealing, so that the said adjacent exterior may be protected from any contact with foreign substances; to provide a sealing means which is practically impossible to remove without leaving visible evidence of
15 the removal, yet which can be easily and readily removed by hand without the use of tools or other implements; to provide a sealing means of maximum effectiveness in the first instance, yet is impossible to remove without showing visible evi-
20 dences of its first removal; to provide a sealing means which is usable and effective with or without an inner gasket; to provide a sealing means which will meet the requirements of the most exacting board of health regulations; to provide
25 a sealing means originally constructed in a plurality of parts, but which, in assembled form, become integral; to insure effective means against the refilling of original containers without visible evidence of such refilling; to provide a sealing part, sufficiently sized to well cover and protect the container opening, thereby affording ample retaining space upon which to securely fasten the plural portion of the complete sealing means;
30 to provide a sealing member or disc, having there-
35 in on a line parallel to its outer circumference, a series of triangular cuts, forming, but not detaching, a series of fan-shaped pieces which may in turn be folded in the direction of the outer circumference of the sealing disc, so as to render
40 the disc of major bulk and thickness adjacent its exterior circumference, and of a lesser and corresponding bulk at points within and parallel to said exterior circumference, all for the purpose of rendering of lesser thickness, that portion of
45 the disc which contacts with the container at its greatest circumference immediately adjacent the container's opening, and of greater thickness at that portion of the disc which contacts the container on the side of said greatest circumference
50 which is positioned away from the container's opening; to provide effective locking means for securing the said disc in position on the container; to number said cuts and fan-shaped pieces in proportion to the size of the disc, so as to remove
55 a substantial portion of the disc at its cut out area and fold same onto the exterior of the disc adjacent its outer circumference, and thereby substantially increase the thickness of said disc at said outer circumference; to provide an exterior ring member of diameter substantially 60 equal to the distance between one of said openings in said disc, and the opening farthest therefrom on the opposite side of the disc; to provide an exterior ring sized to fit snugly over the edges of the disc as they envelope the sides of the container adjacent its opening, adaptable to function so as to force said fan-shaped pieces in the direction of the outer circumference, and onto that portion of the disc adjacent said outer circumference; to thereby securely anchor the disc 65 in position upon and about the opening of the container by sheer force of its thickened outer circumference confined within said ring; to provide a mode of construction and application which produces a significant and outstanding drum-like 70 tautness at that portion of the disc which covers the container opening; to provide a construction and method of application, the various steps of which all function to co-operate to an effective and finished result in an apparent and integral 75 merger; to insure a unit construction by the application of a suitable adhesive to the parts of the device where they contact, parallel to the said exterior circumference, and nowhere else; to provide on the exterior of said ring, a partial cut or 80 incision which will weaken its structure thereabouts so that a tearing pressure there applied results in a removal and partial ruin of said device, rendering it unsuitable for further use; to provide a seal of maximum efficiency and attrac- 85 tiveness at a minimum cost of material; to materially increase the measure of sealer accomplishment; to provide a sealer both neat and close fitting, eliminating elements such as the outstanding and overhanging parts which easily become 90 soiled and are otherwise objectionable; to provide a sealer of major attractiveness which readily blends with desirable color effects, in lettering an ornamental design, for advertising purposes; and to provide the various other advantages and results made evident from the following specification.

I accomplish the objects of my invention by providing a member or disc, having therein on a line parallel to its outer circumference, a series of 105 cuts, forming, but not detaching, a series of fan-shaped pieces which may in turn be folded in the direction of the outer circumference of the sealing disc, so as to render the disc of major bulk and thickness adjacent its exterior circumference, 110

and of a lesser and corresponding bulk at points within and parallel to said exterior circumference, all for the purpose of rendering of lesser thickness, that portion of the disc which contacts 5 with the container at its greatest circumference immediately adjacent the container's opening, and of greater thickness at that portion of the disc which contacts the container on the side of said greatest circumference which is positioned 10 away from the container's opening. I then provide an exterior ring sized to fit snugly over the edges of the disc as they envelop the sides of the container adjacent its opening, adaptable to function so as to force said fan-shaped pieces in 15 the direction of the outer circumference, and onto that portion of the disc adjacent said outer circumference. Optionally, I apply a suitable adhesive to the parts of the device where they contact parallel to the said exterior circumference of said disc. The application of such adhesive at said points, materially contributes to the impossibility of removing the device without visible evidence of such removal. The sealing means herein described is applicable with or without 20 an inner gasket, such use being optional. Said outer sealing ring is provided on its exterior with an incision which weakens its structure thereabouts so that a tearing pressure there applied, results in its removal and partial ruin, 25 rendering it unsuitable for further use.

The series of fan-shaped pieces referred to may optionally be folded inwardly or outwardly onto the surface of the disc adjacent its outer circumference. That portion of the disc adjacent 30 its outer circumference may optionally be fluted to better facilitate its closer formation to the sides of the container adjacent its opening.

While I have illustrated and described a preferred construction for carrying my invention 40 into effect, this is capable of variation or modification without departing from the spirit of the invention. I therefore do not wish to be limited to the exact details of construction herein set forth, but desire to avail myself of such variations 45 and modifications as come within the scope of the appended claims.

Referring to the accompanying drawing which forms a part of this specification and in which similar letters of reference refer to similar parts 50 throughout the various views, Figure 1 shows my improved device as positioned on the top of a milk bottle. Figure 2 shows a half section of the bottle and cap shown in Figure 1. Figure 3 shows a perspective view looking toward the interior of 55 the assembled device. Figure 4 shows a perspective view of the device with a portion of the ring torn away as intended for removal. Figure 5 shows a view of the disc in position over the top of the container, with the ring removed. Figure 6 shows the formation of the disc as initially prepared.

Referring again to the drawing, A shows the container. B shows the sealing disc. C shows the exterior ring. D shows the fan-shaped pieces, 60 cut from the sealing disc and folded onto and upon that portion of the disc adjacent its outer circumference as shown in Figures 5 and 6, said fan-shaped pieces being cut from that portion of the disc designated as E.

70 During the process of application, the sealing disc B, first prepared as shown in Figure 6, is shaped by pressure into the form shown in Figure 5, with the fan-shaped pieces D, extending downwardly as shown in the direction of the outer circumference of the disc. The exterior ring 75

C is then forced down over the top of the disc B into the position shown in Figure 1.

Prior to the application of the exterior ring, a minimum amount of adhesive may be applied, either to the interior of the outer ring C, or to the exterior of the sealing disc B, upon and adjacent to the fan-shaped pieces. When so applied, the adhesive acts to make the sealing disc and outer ring integral.

Having thus described my invention, I claim 85 as new and desire to secure by Letters Patent of the United States of America:

1. In combination with a container having a beaded neck, a closure comprising a cap having a disc portion and a skirt portion, said skirt portion having a series of cuts therein forming a series of tabs spaced from the margin circumferentially thereof, and said tabs being bent downwardly toward said margin so as to make the skirt portion immediately below the bead substantially thicker than the skirt portion overlaying the bead, and an annular fastening ring encircling the skirt portion and tightly engaging the same.

2. A closure, adaptable for use with a container, having a beaded neck, said closure comprising a cap having a disc portion and a skirt portion, said skirt portion having a series of cuts therein forming a series of tabs spaced from the margin circumferentially thereof, and said tabs being bent downwardly toward said margin so as to make the skirt portion immediately below the bead substantially thicker than the skirt portion overlaying the bead, and an annular fastening ring encircling the skirt portion and tightly engaging the same.

3. In combination with a container having a beaded neck, a closure comprising a cap having a disc portion and a skirt portion, said skirt portion having a series of cuts therein forming a series of dovetail tabs hinged to said skirt portion, the edge of said tabs opposite the hinge being longer than the hinge, said tabs spaced from the margin circumferentially of said skirt, said hinges before bending being nearer said margin than said opposite tab edges, said tabs being bent downwardly toward said margin so as to make the skirt portion immediately below the bead substantially thicker than the skirt portion overlaying the bead, and an annular fastening ring encircling the skirt portion and tightly engaging the same.

4. A closure, adaptable for use with a container having a beaded neck, said closure comprising a cap having a disc portion and a skirt portion, said skirt portion having a series of cuts therein forming a series of dovetail tabs hinged to said skirt portion, the edge of said tabs opposite the hinge being longer than the hinge, said tabs spaced from the margin circumferentially of said skirt, said hinges before bending being nearer said margin than said opposite tab edges, said tabs being bent downwardly toward said margin so as to make the skirt portion immediately below the bead substantially thicker than the skirt portion overlaying the bead, and an annular fastening ring encircling the skirt portion and tightly engaging the same.

5. In combination with a container having a beaded neck, a closure comprising a cap having a disc portion and a skirt portion, said skirt portion having a series of cuts therein forming a series of tabs spaced from the margin circumferentially thereof, and said tabs being bent downwardly toward said margin so as to make 145

- the skirt portion immediately below the bead substantially thicker than the skirt portion overlying the bead, an annular fastening ring encircling the skirt portion and tightly engaging 5 the same, and an adhesive applied between the skirt and the fastening ring.
6. A closure, adaptable for use with a container, having a beaded neck, said closure comprising a cap having a disc portion and a skirt portion, said skirt portion having a series of cuts therein forming a series of tabs spaced from the margin circumferentially thereof, and said tabs being bent downwardly toward said margin so as to make the skirt portion immediately 10 below the bead substantially thicker than the skirt portion overlying the bead, an annular fastening ring encircling the skirt portion and tightly engaging the same, and an adhesive applied between the skirt and the fastening ring.
- 15 7. In combination with a container having a beaded neck, a closure comprising a cap having a disc portion and a skirt portion, said skirt portion having a series of cuts therein forming a series of dovetail tabs hinged to said skirt portion, the edge of said tabs opposite the hinge being longer than the hinge, said tabs spaced from the margin circumferentially of said skirt, said 20 tabs being bent downwardly toward said margin so as to make the skirt portion immediately below the bend substantially thicker than the skirt portion overlying the bead, an annular fastening ring encircling the skirt portion and tightly engaging the same, and an adhesive applied between the skirt and the fastening ring.

hinges before bending being nearer said margin than said opposite tab edges, said tabs being bent downwardly toward said margin so as to make the skirt portion immediately below the bead substantially thicker than the skirt portion overlying the bead, an annular fastening ring encircling the skirt portion and tightly engaging the same, and an adhesive applied between the skirt and the fastening ring.

8. A closure, adaptable for use with a container having a beaded neck, said closure comprising a cap having a disc portion and a skirt portion, said skirt portion having a series of cuts therein forming a series of dovetail tabs hinged to said skirt portion, the edge of said tabs opposite the hinge being longer than the hinge, said tabs spaced from the margin circumferentially of said skirt, said hinges before bending being nearer said margin than said opposite tab edges, said tabs being bent downwardly toward said margin so as to make the skirt portion immediately below the bend substantially thicker than the skirt portion overlying the bead, an annular fastening ring encircling the skirt portion and tightly engaging the same, and an adhesive applied between the skirt and the fastening ring.
